Primary Examiner—Brian N. Vinson*Attorney, Agent, or Firm*—Edward L. Brown, Jr.[57] **CLAIM**

The ornamental design for a magnetically mounted caddy, as shown and described.

DESCRIPTION

FIG. 1 is a left side elevational view of the magnetically mounted caddy attached to a horizontal surface. The opposite side elevational view being a mirror image;

FIG. 2 is a front elevational view. The back elevational view being a mirror image;

FIG. 3 is a top view;

FIG. 4 is a bottom view;

FIG. 5 is a left side elevational view, attached to a vertical surface; and,

FIG. 6 is a perspective view from the right rear side.

The broken-line disclosure of horizontal and vertical surfaces in the views is for illustrative purposes only and forms no part of the claimed design.
